(57) **CLAIM**

The ornamental design for a vehicle front bumper, as
shown and described.

DESCRIPTION

FIG. 1 is a perspective view of a front bumper in accordance
with an embodiment of the present invention;

FIG. 2 is a front view of the front bumper shown in FIG. 1;
FIG. 3 is a side view of the vehicle of the front bumper
shown in FIG. 1; and,

FIG. 4 is a top view of the front bumper of FIG. 1.
The bottom and rear views of the front bumper are not part
of the claimed design. The sides of the front bumper are
mirror images of one another. The broken lines, including
for the attachment portion of the bumper to a vehicle,
illustrate the environment of the design and are not part of
the claimed design.
